UNITED STATES PATENT OFFICE.

FRANK C. EMRICK, OF KALAMAZOO, MICHIGAN, ASSIGNOR TO KALAMAZOO SANITARY MANUFACTURING COMPANY, OF KALAMAZOO, MICHIGAN.

PRESS.

Application filed October 21, 1922. Serial No. 595,961.

To all whom it may concern:

Be it known that I, FRANK C. EMRICK, citizen of the United States, residing in city and county of Kalamazoo, State of Michigan, have invented certain new and useful Improvements in Presses, of which the following is a specification.

This invention relates to improvements in presses.

10 My improved press is especially designed by me for a molding press and I have illustrated and described the same in this application as I have embodied for that purpose. Various features of my improvements are, however, adapted for use in other relations.

The main objects of this invention are:

First, to provide an improved press which is automatic in its operation.

20 Second, to provide an improved press for molding comparatively large objects, such as saggars, which is adapted to receive the clay in "slugs", the molded articles being automatically discharged.

25 Third, to provide an improved automatic press machine which is of large capacity.

Fourth, to provide an improved automatic press in which the parts are so constructed and arranged as to be very durable.

30 Further objects, and objects pertaining to details and economies of construction and operation will definitely appear from the detailed description to follow.

35 I accomplish the objects of my invention by the devices and means described in the following specification. The invention is clearly defined and pointed out in the claims.

40 A structure which is a preferred embodiment of my invention is clearly illustrated in the accompanying drawing forming a part of this application, in which:

Fig. I is a perspective view of my improved press, the plunger being shown in its actuated position.

45 Fig. II is a perspective view from the discharge side of the machine, the molds or forms being omitted.

Fig. III is a detail horizontal section on a line corresponding to line 3—3 of Fig. II, the forms being shown in position and a fragment of the discharge conveyor being shown in its relation to the machine.

50 Fig. IV is an enlarged detail section on a

line corresponding to line 4—4 of Fig. V 55 showing details of the mold and means for locking it in closed position during the molding operation.

Fig. V is a detail plan view of the locking or clamping mechanism, partly in section 60 on a line corresponding to line 5—5 of Fig. I.

Fig. VI is a fragmentary view showing parts of the molding turret or table actuating means. 65

Fig. VII is a fragmentary plan view of parts of the mechanism shown in Fig. VI.

Fig. VIII is a detail section on a line corresponding with line 8—8 of Fig. VI. 70

Fig. VIII^A is a detail section on a line corresponding to line 8^A—8^A of Fig. VI showing further details of the turret actuating mechanism.

Fig. IX is an enlarged detail section on a line corresponding to line 9—9 of Figs. I, X, and XI showing details of the hydraulic plunger control. 75

Fig. X is a detail section on a line corresponding to line 10—10 of Fig. IX showing further details of the hydraulic plunger control means. 80

Fig. XI is a detail view partly in section on a line corresponding to line 11—11 of Figs. X and XII. 85

Fig. XII is a detail section on a line corresponding to line 12—12 of Fig. XI.

Fig. XIII is a fragmentary side elevation showing details of the control valve operating means. 90

Fig. XIV is a detail side elevation of parts of the automatic plunger release mechanism.

Fig. XIV^A is a detail view showing further details of the automatic release mechanism. 95

Fig. XV is a fragmentary elevation of parts of the turret control mechanism.

Fig. XVI is a detail view partly in section on a line corresponding to line 16—16 100 of Fig. XVII showing details of the mold side lock or clamp acting when the mold is in molding position.

Fig. XVII is a detail vertical section on a line corresponding to line 17—17 of Fig. XVI. 105

Fig. XVIII is a detail view of the discharging mechanism.

Fig. XVIII^A is a perspective view of one of the articles which the machine illustrated is especially designed to mold.

In the drawing the sectional views are taken looking in the direction of the little arrows at the ends of the section lines and similar reference numerals refer to similar parts throughout the several views.

Referring to the drawing, I provide a base 1, which in practice is a casting of suitable size to effectively support the operating parts. The turret or table 2 is mounted on suitable bearings carried by the upright 3. The details of these bearings are, however, not illustrated as they form no part of this invention.

The base has mounted thereon a pair of uprights 4 disposed at one side of the table 3 and carrying at their upper ends the head piece 5. A third upright 6 is disposed centrally of the table.

The table in the structure illustrated carries four molds consisting of the sections 7 and 8, the table itself constituting the bottom of the mold. The outer section 8 is provided with an arm 9 pivoted at 10 to the bracket 11. This outer section is also provided with a handle 12 for opening and closing the same. The table or turret is moved with a step by step movement to bring it into operative relation to the molding plunger and to advance it after molding to discharging position, also, while at rest, the operator may close the mold and place the clay in the molds as they successively come to charging position.

The feed mechanism for the table comprises a plunger 13 mounted below the table. This plunger is provided with a head 14 (see Fig. VI). This head carries a pin 15 which is projected by the spring 16 into engagement with the rollers 17 supported in radial ways 18 on the under side of the table. A cylinder 19 is provided so that the plunger is actuated by fluid under pressure. The rollers travel in the radial ways 18 so that when the plunger is actuated the table is advanced one step. The pin 15 is engaged successively with the rollers, and there being four as shown in Fig. III, each stroke of the plunger operates the table a quarter turn.

The pin 15 is locked in its engaged and disengaged positions by catches 18' pivoted on the plunger head and held yieldingly in engaging position by the springs 15''. Only one of these is shown in detail as in Fig. VIII^A, the other being a duplicate of it, although disposed in reversed position. Both are indicated by dotted lines in Fig. VI. The pin has a notch 15''' adapted to receive these catches, one of the catches being higher than the other holds the pin in its projected position and the other in its retracted position. Trips 16' are provided

for releasing these catches at the end of the stroke of the plunger, the releasing being timed so that the pin may be retracted or withdrawn from the rollers.

The driving pin 15 is automatically retracted at the end of each work stroke, the head 20 of the pin being engaged by the U-shaped trip 21. This trip 21 is mounted for vertical movement, it being provided with a plunger operating in a cylinder 22. The plunger is forced to its retracted or pin releasing position by means of the fluid under pressure and is held in that position by the dog 24 pivoted at 25 to the bracket 26, the trip being projected to the position illustrated in dotted lines, which is the driving pin disengaging position, by means of the coiled spring 27 shown conventionally in Fig. VI.

The admission of the actuating fluid to the cylinder 19 is controlled by the valve 28, the details of which are not illustrated. The valve 28 is connected to the cylinder 19 by means of the pipe 29. The valve 28 is controlled from the trip plunger which is provided with an arm 30 having a roller 31 which engages an arm 32 on the stem of the valve 28. This arm 32 has an inclined groove 33 with which the roller 31 on the arm 30 coacts so that as the trip plunger reciprocates vertically the stem of the valve 28 is given a rotary motion (see Figs. VI, VII and VIII). The groove 33 of the arm 32 is provided with a side wall 35 pivoted at 36 and held in closed position by the cam shaped locking disk 37 having a flattened side 38. This disk is held normally in engaging position by means of the coiled spring 39 connected to the pin 40 on the locking disk and to a pin 41 on the arm 32. This locking disk is released and the valve returned to neutral by the tappet arm 42 carried by the head 14 of the table actuating plunger 13.

This tappet arm is adapted to release the locking disk and engage the roller 44 on the arm 32, the tappet arm having a cam portion 45 adapted to engage the roller 44 (see dotted lines in Fig. VII), the roller being engaged after the locking disk has been released, thereby permitting the swinging of the valve to neutral and the return movement of the trip plunger.

The dog 24 is connected to the bell crank lever 47 pivoted at 48 and connected by the link 49 to a bell crank lever 50 pivoted at 51. This bell crank lever 50 is in turn connected by the link 52 to the lever 53 (see Figs. VI and XV), the lever 53 being operated by the rod 54 connected to the main molding plunger 55 for synchronizing the mechanism.

The rod 54 is provided with a pivoted dog 56 for actuating the roller 57 on the lever 53, passing up one side of the dog on

the down stroke of the rod, or passing over the dog as shown by full lines in Fig. XV. On the down stroke of the rod the dog drops out by gravity after the lever has passed it so that on the up stroke of the rod the roller must travel on the other side of the dog, thereby actuating the lever as shown in Fig. XV.

The valve 28, as stated, controls the connection 29 leading to the cylinder 19. The intake or pressure connection 58 is connected to the power or pressure line indicated at 59, this connection, however, not being illustrated. The pipe 29' connects the valve 15 to the return end of the cylinder 19.

30 is an exhaust connection for the valve 28. The connection 61 for the trip cylinder 22 will be described later as it is controlled from the manually operated valve for controlling the ejector.

The ram or molding plunger 55 is provided with a cylinder 62 mounted on the frame headpiece 5. An exhaust or overflow tank 63 is mounted above the hydraulic cylinder 62, it being connected to the cylinder 64. Mounted upon the cylinder 62 is the cylinder 65 in which there is a plunger 66 having a cross head 67 at its upper end to which the rods 54 are connected. The rods 54 are arranged through the headpiece 5 of the frame and secured to the head of the ram, thus providing a return means for the ram. This return cylinder is controlled by a valve designated generally by the numeral 69, the details of which are not illustrated. This valve is controlled by the cam-shaped tappets 70 on the table 2 which engage the lever 71 pivoted on the frame 72 and connected by the rod 73 to the 40 valve.

This valve 69 controls the admission of the actuating fluid to the main cylinder 62 and also to the return cylinder 65, the connection 74 leading to the upper end of the cylinder 105 and through the connection 106 to the main cylinder 62. The valve is connected by the pipe 75 to the lower end of the return cylinder 65 and is connected to the power supply by the pipe 76. This pipe 50 76 is provided with a shut-off valve 77 for use when it is desired to cut off the operation of the machine.

The valve 69 is automatically operated to cut off the supply of fluid to the main cylinder and deliver to the return cylinder by means of a pressure actuated device which for convenience I designate as an unloader. This comprises a cylinder 78 having inlet connection 79 to the pipe 74 and through the 60 connection described to the cylinder 62. The plunger 80 of this device has a pressure spring 81, the upper end of the spring being supported by a yoke 82 adjustable upon the rod 83. The plunger acts upon the spring through the toggle designated

generally by the numeral 84, the purpose of this spring and toggle action being to operate the device with a snap action. When the toggle is raised sufficiently to overcome the tension of the spring and actuate the 70 toggle, a lug 85 on the toggle head 82 engages a tappet 86 on a sleeve 87 mounted on the rod 87'. This sleeve is connected to the arm 88 of the valve 69 so that when the pressure in the cylinder reaches a predetermined point, that is, a point that will overcome the tension of the spring 81, the unloader device operates to actuate the valve 69, opening the main cylinder to the exhaust and the return cylinder to power, thereby 80 retracting the plunger.

To provide for rapid initial movement of the ram I connect the same to the reservoir 63 through the passage 89 which is controlled by the valve 90 (see Figs. IX, X and 85 XI), the operation being to admit the rapid passage of the power fluid through the passage 89 until the final high pressure point is reached, when this passage is cut off by the closing of the valve 90 and the 90 power for the remaining movement is supplied through the valve 69 described. The valve 90 is provided with racks 91 actuated by the coacting rack 92 movable transversely thereof, this rack 92 being actuated by the 95 plunger 93 within the cylinder 94. This cylinder 94 is connected by the pipes 95 and 96 to the valve 97 which is operated from the rod 54, the valve having an arm 98 and the rod having an arm 99 secured thereto to coact with the valve arm 98 as shown in Fig. XIII.

Owing to the high pressure to which the mold is subjected when the ram is actuated it is necessary to lock the mold to the table 105 and also to lock the mold sections together. To accomplish the latter, I provide a pair of reciprocating channel-shaped locking members 100 having a series of balls 101 at each side to coact with the mold flanges 102 110 (see Figs. II, XVI, and XVII). The grooves or channels of the locking members 100 are slightly tapered and the flanges 102 are correspondingly tapered so that they are locked very firmly together and exuding 115 of clay between the joints of the sections is prevented.

The locking members 100 are connected by the yoke 103 and are operated by means of the plunger 104 coacting with the cylinder 105. The fluid connections for this cylinder have been described.

The molds are clamped to the table at the molding point by clamping means comprising a pair of jaws 107 supported upon a cross piece 108 which has a limited sliding movement between the bars 108' supported by the yoke-like frame piece 111 mounted on the uprights 4. These jaws are actuated by the plunger 110, the plunger being pro- 125 130

vided with a rod extension 110' on which the cross piece 108 is mounted. The outer ends of the jaws 107 are connected by the links 113 to the plunger, the links being pivoted to the plunger at 114 so that, as the plunger is forced inwardly, the jaws are actuated to clamp the mold to the bed and on the reverse movement they are opened up.

A coiled spring 115 is arranged between the plunger and the cross piece 108" to return the plunger. Coiled springs 115' are arranged between the cross piece 108" and the cross piece 108. These serve to throw the cross piece 108" forward when the forward movement of the plunger compresses the spring 115 sufficiently to overcome the tension, that is, the spring 115 is of such tension as to move the cross piece 108 rearwardly against the tension of the springs 115'. However, when the plunger moves forward under the actuating fluid the springs 115' are of sufficient strength to move the jaws forward to clamping position. This movement is required owing to the shape of the molds.

The outer section 8 of the mold is, in the embodiment illustrated, swung open by hand; the inner section is then pushed forward to discharge the molded article to the conveyor 117 or other suitable receiving table. This discharge is also a fluid operated device and consists of the pusher 118 provided with a pair of slides or carriages 119 having pinions 120 coacting with racks 121, the object being to reciprocate the pusher in a straight line. This pusher is actuated by a plunger 122 and cylinder 123. The ends of the cylinder are connected with the valve 124 by the conduits 125 and 126. This valve is not detailed, but is provided to insure the complete actuation of the valve, that is, the spring is connected to the arm 129 of the valve so that the valve is actuated with a snap-like action. This valve is connected to the power line by the conduit 130. This valve also controls the trip plunger cylinder 22, the pipe 61 leading to this valve.

Assuming that the machine is in operation and the molds all closed as shown in Fig. III, the operator grasping the handle 12 swings the outer section of the mold to the position shown by dotted lines, and then grasping the lever 127 opens the valve 124 which controls the ejector plunger 122 in the cylinder 123. This valve also controls the retracting trip 21 for the driving pin 15, the valve being suitably connected to the cylinder 22 for the trip plunger. The opening of the mold and the operation of the lever 127 are the only manual operations, the remainder being entirely automatic, the mechanisms being timed so that the molding plunger operates while the table is at

rest and when retracted and the table or turret operating when the plunger is actuated.

The table is actuated by the plunger 13 in the cylinder 19 which is controlled by 70 the valve 28. The details of this valve are not illustrated but the valve 28 is connected to the cylinder 19 by means of the pipe 29.

The valve 28 is automatically controlled by the trip plunger 21 which has an arm 75 engaging the arm 32 on the stem of the valve 28. The ram or molding plunger 55 has a cylinder 62 and to this is connected an exhaust or storage tank 63. The return cylinder 65 is provided with a plunger 66. 80 This return cylinder is controlled by the valve designated generally by the numeral 69 which is controlled by tappets 70 on the table, thus timing the movements of the parts. This valve 69 also controls the admission of the actuating fluid to the molding cylinder.

The cut-off valve 77 is provided when it is desired to stop the machine. When the molds are in molding position they are automatically clamped to the table and locked together by means actuated by the plunger 104 and cylinder 105. These cylinders are connected to the main or molding plunger so that they are actuated simultaneously 95 with the molding plunger.

Having thus described my invention what I claim as new and desire to secure by Letters Patent is:

1. In a molding machine, the combination 100 of a molding table, molds comprising complementary mold members having bottom flanges and upwardly tapered flanges at their abutting edges, said molds being disposed on said table which constitutes the 105 bottom of the molds, a molding plunger, a cylinder therefor, mold locking members channeled to embrace said flanges and having opposed upwardly inclined ways in the sides of the channels with balls therein 110 coacting with said mold member flanges, actuating means for said mold locking members, means for clamping the mold to the table at molding position comprising a pair of coacting clamping jaws, one of which 115 is adapted to engage the table and the other the bottom flange of a mold, actuating means for said jaws comprising a plunger operatively connected to the jaws and a coacting cylinder, and fluid control connections for said cylinders whereby their actuation is timed.

2. In a molding machine, the combination 120 of a molding table, molds comprising complementary mold members having upwardly 125 tapered flanges at their abutting edges, said molds being disposed on said table which constitutes the bottom of the molds, a molding plunger, a cylinder therefor, mold locking members channeled to embrace said 130

flanges and having opposed upwardly inclined ways in the sides of the channels with balls therein coacting with said mold member flanges, actuating means for said mold locking members, and fluid control connections for said cylinders whereby their actuation is timed.

3. In a molding machine, the combination of a molding table, molds comprising complementary mold members having bottom flanges at their abutting edges, said molds being disposed on said table which constitutes the bottom of the molds, a molding plunger, a cylinder therefor, mold locking members channeled to embrace said flanges, actuating means for said mold locking members, means for clamping the mold to the table at the molding position comprising a pair of coacting clamping jaws, one of which is adapted to engage the table and the other the bottom flange of a mold, actuating means for said jaws comprising a plunger operatively connected to the jaws and a coacting cylinder, and fluid control connections for said cylinders whereby their actuation is timed.

4. In a molding machine, the combination of a molding table, molds comprising complementary mold members having flanges at their abutting edges, said molds being disposed on said table which constitutes the bottom of the molds, a molding plunger, a cylinder therefor, mold locking members channeled to embrace said flanges, actuating means for said mold locking members, and fluid control connections for said cylinders whereby their actuation is timed.

5. In a molding machine, the combination of a molding table, molds comprising complementary mold members having flanges at their abutting edges, said molds being disposed on said table which constitutes the bottom of the molds, a molding plunger, a cylinder therefor, mold locking members channeled to embrace said flanges, a connecting yoke for said mold locking members, actuating means for said mold locking members comprising cylinders and coacting plungers connected to said yoke, and fluid control connections for said cylinders whereby their actuation is timed.

6. In a molding machine, the combination of a molding table, molds disposed on said table and comprising complementary mold members having bottom flanges and flanges at their abutting edges, a molding plunger, actuating means therefor, mold locking members channeled to embrace said flanges, actuating means for said mold locking members, means for clamping the mold to the table at molding position comprising a pair of coacting clamping jaws, one of which is adapted to engage the table and the other the bottom flange of a mold, and actuating means for said jaws.

7. In a molding machine, the combination of a molding table, molds disposed on said table and comprising complementary mold members having flanges at their abutting edges, a molding plunger, actuating means therefor, mold locking members channeled to embrace said flanges, actuating means for said mold locking members.

8. In a molding machine, the combination of a molding table, molds disposed on said table and comprising complementary mold members having bottom flanges and flanges at their abutting edges, a molding plunger, actuating means therefor, mold locking members channeled to embrace said flanges, and having opposed ways in the sides of the channels with balls therein coacting with said mold member flanges, actuating means for said mold locking members.

9. In a molding machine, the combination of a molding table, molds disposed on said table and comprising complementary mold members having bottom flanges, a molding plunger, actuating means therefor, mold locking members, actuating means for said mold locking members, means for clamping the mold to the table at molding position, comprising a pair of coacting clamping jaws, one of which is adapted to engage the table and the other the bottom flange of a mold, and actuating means for said jaws.

10. In a molding machine, the combination of a molding table, molds disposed on said table and comprising complementary mold members, a molding plunger, actuating means therefor, mold locking members, actuating means for said mold locking members, means for clamping the mold to the table at molding position.

11. In a molding machine, the combination of a molding table, molds disposed on said table having bottom flanges, a molding plunger, actuating means therefor, means for clamping the mold to the table at molding position, comprising a pair of coacting clamping jaws, one of which is adapted to engage the table and the other the bottom flange of a mold, and actuating means for said jaws.

12. In a molding machine, the combination of a molding table, molds disposed on said table and comprising complementary mold members having flanges at their abutting edges, a molding plunger, actuating means therefor, mold locking members coacting with said flanges, actuating means for said mold locking members, and means for controlling said plunger and locking member actuating means whereby their actuation is timed.

13. In a molding machine, the combination with a molding table, of molds comprising complementary sections having bottom flanges and flanges at their abutting edges, said molds resting on the table which con-

stitutes the bottom of the molds, a molding plunger, a coacting cylinder, mold locking members channeled to engage said flanges to clamp the mold members together, actuating means for said mold lock members comprising plungers and coacting cylinders, means for clamping the molds to the table at molding position comprising a supporting frame, coacting clamping jaws, one of which is adapted to engage the table and the other the bottom flange of a mold, a supporting member on which said jaws are pivotally mounted disposed on said frame for limited movement thereon, actuating means for said jaws comprising a plunger and a coacting cylinder, links connecting the outer ends of said jaws to said plunger, a return spring for said plunger, and a spring arranged to act on said jaw supporting member whereby when the plunger is actuated to an extent counterbalancing the said return spring said second spring moves said supporting member to clamping position.

14. In a molding machine the combination with a molding table, of molds comprising complementary sections having bottom flanges, said molds resting on the table which constitutes the bottom of the molds, a molding plunger, a coacting cylinder, means for clamping the molds to the table at molding position comprising a supporting frame, coacting clamping jaws, one of which is adapted to engage the table and the other the bottom flange of a mold, a supporting member on which said jaws are pivotally mounted disposed on said frame for limited movement thereon, actuating means for said jaws comprising a plunger and a coacting cylinder, links connecting the outer ends of said jaws to said plunger, a return spring for said plunger, and a spring arranged to act on said jaw supporting member whereby when the plunger is actuated to an extent counterbalancing the said return spring said second spring moves said supporting member to clamping position.

15. In a molding machine, the combination with a molding table, of molds comprising complementary sections, a molding plunger, a coacting cylinder, mold locking members adapted to clamp the mold members together in molding position, coacting pivoted clamping jaws, one of which is adapted to engage the table and the other the mold, actuating means for said jaws comprising a plunger and a coacting cylinder, and links connecting the outer ends of said jaws to said plunger.

16. In a molding machine, the combination with a molding table, of molds, a molding plunger, a coacting cylinder, coacting pivoted clamping jaws, one of which is adapted to engage the table and the other the mold, actuating means for said jaws comprising a plunger and a coacting cylin-

der, and links connecting the outer ends of said jaws to said plunger.

17. In a molding machine, the combination with a molding table, of molds adapted to be disposed on said table, a molding plunger, actuating means therefor, means for clamping the molds to the table at molding position, comprising a supporting frame, coacting clamping members, a supporting member on which said clamping members are mounted disposed on said frame for limited movement thereon, actuating means for said clamping members comprising a plunger and a coacting cylinder, a return spring for said plunger, and a spring arranged to act on said supporting member whereby when the plunger is actuated to an extent counterbalancing the said return spring said second spring moves said supporting member to clamping position.

18. In a molding machine, the combination with a molding table, of molds adapted to be disposed on said table, a molding plunger, actuating means therefor, means for clamping the molds to the table at molding position, comprising a supporting frame, coacting clamping members, and actuating means for said clamping members comprising a plunger and a coacting cylinder.

19. In a molding machine, the combination with a molding table, of molds disposed on said table so that the table constitutes the bottoms of the molds, a molding plunger, actuating means therefor, and means for clamping the molds to the table at molding position.

20. In a molding machine, the combination with a rotating work table, a plurality of molds comprising complementary members mounted upon said table, the table constituting the bottom of the mold, the outer mold member being provided with an arm at one side pivoted on said table so that such outer mold member may be swung to one side to clear the inner member, a radially reciprocating ejector member mounted centrally of said table to successively coact with the inner mold members to eject the molded articles from the table, means for actuating said ejector member comprising a plunger and coacting cylinder, a pair of racks, pinions on said plunger member coacting with said racks whereby the plunger member is guided, and a valve for controlling said cylinder.

21. In a molding machine, the combination with a rotating work table, a plurality of molds comprising complementary members mounted upon said table, the table constituting the bottom of the mold, the outer mold member being provided with an arm at one side pivoted on said table so that such outer mold member may be swung to one side to clear the inner member, a radially reciprocating ejector member mount-

ed centrally of said table to successively coat with the inner mold members to eject the molded articles from the table, means for actuating said ejector member 5 comprising a plunger and coacting cylinder, and a valve for controlling said cylinder.

22. In a molding machine, the combination with a rotating work table, a plurality of molds comprising complementary members mounted upon said table, the table constituting the bottom of the mold, the outer mold member being provided with an arm at one side pivoted on said table so that such outer mold member may be swung 10 to one side to clear the inner member, a radially reciprocating ejector member mounted centrally of said table to successively coat with the inner mold members to eject the molded articles from the table, 15 means for actuating said ejector member, a pair of racks, pinions on said plunger member coacting with said racks whereby the plunger member is guided, and a valve for controlling said cylinder.

23. In a molding machine, the combination with a rotating work table, a plurality of molds comprising complementary members, the outer mold member being mounted on said table so that it may be adjusted 20 to clear the inner member, an ejector member adapted to successively coat with the inner mold members to eject the molded articles from the table, means for actuating said ejector member, comprising a plunger 25 and coacting cylinder, a pair of racks, pinions on said plunger member coacting with said racks whereby the plunger member is guided, and a valve for controlling said cylinder.

24. In a molding machine, the combination with a rotating work table, a plurality of molds comprising complementary members, the outer mold member being mounted on said table so that it may be adjusted 30 to clear the inner member, an ejector member adapted to successively coat with the inner mold members to eject the molded articles from the table, means for actuating said ejector member comprising a plunger and coacting cylinder, and a valve for controlling said cylinder.

25. In a molding machine, the combination with a rotating work table, a plurality of molds comprising complementary members, the outer mold member being mounted 35 on said table so that it may be adjusted to clear the inner member, an ejector member adapted to successively coat with the inner mold members to eject the molded articles 40 from the table, means for actuating said ejector member, a pair of racks, pinions on said plunger member coacting with said racks whereby the plunger member is guided, and a valve for controlling said cylinder.

26. The combination with a rotatable table, a work plunger, a coacting cylinder, a return plunger for said work plunger, a coacting cylinder for said return plunger, means for actuating said table comprising a plunger and coacting cylinder, ways disposed radially on said table, rollers traveling on said ways, said table actuating plunger being provided with a reciprocating pin adapted to engage said rollers, a spring for projecting said pin, catches for locking said pin in its retracted and projected position, means for releasing said catches at the ends of the stroke of the plunger, a pin releasing means comprising a plunger and coacting cylinder, said pin releasing plunger being adapted to engage said pin at the end of the work stroke of the table actuating plunger, a return spring 50 for said pin releasing plunger, a dog for holding said pin releasing plunger in its pin releasing position, a valve for controlling said table actuating plunger, a tappet on said table actuating plunger for actuating said valve, and means for releasing said dog operatively connected with said return plunger.

27. The combination with a rotatable work table, a work plunger, a coacting cylinder, a return plunger for said work plunger, a coacting cylinder for said return plunger, means for actuating said table comprising a plunger and coacting cylinder, ways disposed radially on said table, rollers traveling in said ways, said table actuating plunger being provided with a reciprocating pin adapted to engage said rollers, a pin releasing means comprising a plunger and a coacting cylinder, said pin releasing plunger being adapted to engage said pin at the end of the work stroke of the table actuating plunger, a dog for holding said pin releasing plunger in its pin releasing position, a valve for controlling said table actuating plunger, a tappet on said table actuating plunger for actuating said valve, and means for releasing said dog operatively connected with said return plunger.

28. The combination with a rotatable table, a work plunger, means for actuating said work plunger, means for actuating said table comprising a plunger and coacting cylinder, ways disposed radially on said table, a roller traveling in each said ways, said table actuating plunger being provided with a reciprocating pin adapted to successively engage said rollers, a spring for projecting said pin, catches for locking said pin in its retracted and projected positions, means for releasing said catches at the ends of the stroke of the plunger, a pin releasing means comprising a plunger and a coacting cylinder, said pin releasing plunger being adapted to engage said pin at the end of the work stroke of said table actuating

plunger, a return spring for said pin releasing plunger, a dog for holding said pin releasing plunger in its pin releasing position, a valve for controlling said table actuating plunger, and a tappet on said table actuating plunger for closing said valve.

29. The combination with a rotatable table, a work plunger, means for actuating said work plunger, means for actuating said table comprising a plunger and coacting cylinder, ways disposed radially on said table, a roller traveling in each said ways, said table actuating plunger being provided with a reciprocating pin adapted to successively engage said rollers, a pin releasing means comprising a plunger and a coacting cylinder, said pin releasing plunger being adapted to engage said pin at the end of the work stroke of said table actuating plunger, a dog for holding said pin releasing plunger in its pin releasing position, a valve for controlling said table actuating plunger, and a tappet on said table actuating plunger for closing said valve.

30. The combination with a rotatable table, a work plunger, means for actuating said work plunger, means for actuating said table comprising a plunger and coacting cylinder, ways disposed radially of said table, a roller mounted in each way, means for successively engaging said plunger with said rollers, and an automatic control therefor.

35. 31. The combination of a work plunger, a cylinder therefor, a return plunger for said work plunger, a cylinder therefor, a fluid tank, a valved connection therefor to said work plunger cylinder, a plunger for actuating said valve, a control valve for said work and return cylinders, pressure actuated means for controlling said valve comprising a cylinder connected to said work plunger cylinder, a plunger therefor, a governing spring, and toggle means coacting with said spring for controlling the movement of said plunger.

32. The combination of a work plunger, a cylinder therefor, a return plunger for said work plunger, a cylinder therefor, a control valve for said work and return cylinders, pressure actuated means for controlling said valve comprising a cylinder connected to said work cylinder, a plunger therefor, a governing spring, and toggle means coacting with said spring for controlling the movement of said plunger.

33. The combination of a work plunger, a cylinder therefor, a return plunger for said work plunger, a cylinder therefor, a fluid exhaust tank, a valved connection therefor to said work cylinder, a plunger for actuating said valve, a control valve for said work and return cylinders, and pressure actuated means for controlling said valve.

34. The combination of a work plunger, a cylinder therefor, a return plunger for said work plunger, a cylinder therefor, a crosshead on said return plunger, rods connecting said crosshead to said work plunger, and a control valve for said work and return cylinders.

35. In a molding machine, the combination of a rotatable table, means for actuating said table with a step by step movement comprising a cylinder and coacting plunger, molds disposed on said table which constitutes a bottom therefor, said molds comprising complementary mold members, the outer of which is pivotally mounted upon the table, the inner mold members being slidable upon the table, said mold members having abutting flanges at their meeting edges, a molding plunger, a coacting cylinder, means for returning said molding plunger comprising a plunger and cylinder, a control valve for said molding and return cylinders, a pressure actuated means for controlling said valve, mold locking members coacting with said flanges, actuating means for said mold locking members comprising cylinders and coacting plungers, means for clamping the mold to the table at molding position, actuating means for said clamping means comprising a cylinder and coacting plunger, an ejecting means comprising a cylinder and a plunger adapted to engage the inner mold members as they are successively brought to discharging position, and fluid delivery and control members for the several cylinders whereby the actuation of the parts is timed.

36. In a molding machine, the combination of a rotatable table, means for actuating said table with a step by step movement, comprising a cylinder and coacting plunger, molds disposed on said table, a molding plunger, a coacting cylinder, means for returning said molding plunger comprising a plunger and cylinder, a control valve for said molding and return cylinders, a pressure actuated means for controlling said valve, an ejecting means comprising a cylinder and a plunger adapted to engage the inner mold members as they are successively brought to discharging position, and a fluid delivery and control members for the several cylinders whereby the actuation of the parts is timed.

37. In a molding machine, the combination of a rotatable table, means for actuating said table with a step by step movement comprising a cylinder and coacting plunger, molds disposed on said table which constitutes a bottom therefor, said molds comprising complementary mold members, the outer of which is pivotally mounted upon the table, the inner mold members being slidable upon the table, said mold members having abutting flanges at their meeting edges, a

- molding plunger, a coacting cylinder, mold locking members coacting with said flanges, actuating means for said mold locking members comprising cylinders and coacting plun- 5 gers, means for clamping the mold to the table at molding position, actuating means for said clamping means comprising a cylinder and coacting plunger, an ejecting means comprising a cylinder and a plunger 10 adapted to engage the inner mold members as they are successively brought to discharging position, and fluid delivery and control members for the several cylinders whereby the actuation of the parts is timed.
- 15 38. In a molding machine, the combination of a rotatable table, means for actuating said table with a step by step movement, comprising a cylinder and coacting plunger, molds disposed on said table, a molding 20 plunger, a coacting cylinder, an ejecting means comprising a cylinder and a plunger adapted to engage the inner mold members as they are successively brought to discharging position, and fluid delivery and control 25 members for the several cylinders whereby the actuation of the parts is timed.
39. In a molding machine, the combination of a rotatable table, means for actuating said table with a step by step movement, 30 comprising a cylinder and coacting plunger, molds disposed on said table which constitutes a bottom therefor, said molds comprising complementary mold members, the outer of which is pivotally mounted upon the 35 table, the inner mold members being slide- able upon the table, said mold members having abutting flanges at their meeting edges, a molding plunger, a coacting cylinder, means for returning said molding plunger 40 comprising a plunger and cylinder, a control valve for said molding and return cylinders, a pressure actuated means for controlling said valve, mold locking members coacting with said flanges, actuating means for said 45 mold locking members comprising cylinders and coacting plungers, means for clamping the mold to the table at molding position, and actuating means for said clamping means comprising a cylinder and coacting
- plunger, and a fluid delivery and control 50 members for the several cylinders whereby the actuation of the parts is timed.
40. In a molding machine, the combination of a rotatable table, means for actuating said table with a step by step movement 55 comprising a cylinder and coacting plunger, molds disposed on said table which constitutes a bottom therefor, said molds comprising complementary mold members, the outer of which is pivotally mounted upon the 60 table, the inner mold members being slide- able upon the table, said mold members having abutting flanges at their meeting edges, a molding plunger, a coacting cylinder, mold locking members coacting with said flanges, 65 actuating means for said mold locking members comprising cylinders and coacting plun- gers, means for clamping the mold to the table at molding position, actuating means for said clamping means comprising a cyl- 70 inder and coacting cylinder, and a fluid de- livery and control members for the several cylinders whereby the actuation of the parts is timed.
41. The combination of a work cylinder 75 and coacting plunger, a return cylinder and coacting plunger, an exhaust reservoir dis- posed above said work cylinder and connect- ed thereto so that on the return stroke of the work plunger the actuating fluid is delivered 80 to said exhaust reservoir, a valve controlling the connection for said work cylinder and exhaust reservoir, a control valve for said work and return cylinders, and operating 85 connections for said valves.
42. The combination of a work cylinder and coacting plunger, a return cylinder and coacting plunger, an exhaust reservoir connected to said work cylinder, a valve con- nection therefor to said work cylinder, and a 90 control valve for said work cylinder opera- tively associated with said exhaust reservoir whereby the fluid is permitted to flow from said exhaust reservoir by gravity during the initial movement of the work plunger.

In witness whereof, I have hereunto set my hand and seal.

FRANK C. EMRICK. [L. s.]
